ATTORNEY

UNITED STATES PATENT OFFICE.

HARRY M. YOUNG, OF WEBSTER GROVES, MISSOURI.

SURGICAL APPLIANCE.

Application filed January 30, 1928. Serial No. 250,536.

This invention relates generally to surgical appliances.

It is well recognized today that the flesh of a capon is the juiciest, sweetest, most tender, and perhaps the most nutritious of any known meat. Further, capons grow to a larger size than the ordinary male fowl or rooster and command higher market prices. As a result, caponizing is being practiced 10 on an increasingly large extent in many sections of the country, and my present invention has for its chief object the provision of a surgical appliance that is especially adapted for facilitating the act of caponizing.

My invention has, as an additional object, the provision of an appliance for the purpose stated which is of simple, inexpensive structure, which is easily and conveniently 20 usable, and which is efficient and satisfactory in the performance of its intended functions.

And with the above and other objects in view, my invention resides in the novel features of form, construction, arrangement, and combination of parts hereinafter described and pointed out in the claims.

In the accompanying drawing, Figure 1 is a plan view of a caponizing surgical appliance embodying my invention;

Figure 2 is a side elevational view of the appliance; and

Figures 3, 4, and 5 are detail sectional views taken, respectively, on the lines 3—3, 35 4—4, and 5—5, Figure 1.

Referring now more in detail and by reference characters to the drawing, which illustrates a preferred embodiment of my invention, the appliance includes a preferably oblong-rectangular plate or table A constructed of wood or other suitable material and adapted for support, preferably detachably for convenient portability, upon a standard B, as shown. Suitably fixed to, 40 and upstanding from the opposite ends of, table A, are brackets 1, 1, formed upon their upper or free ends with registering grooves or recesses, as at 2, for purposes later appearing. Adjacent an end, table A is preferably provided with an opening, as at 3, to conveniently accommodate an instrument-containing vessel, not shown.

The fowl engaging or holding member of the appliance includes a body portion C constructed preferably of a suitably elongated

rigid metallic strip or bar of circular section. At one end, strip C is preferably arcuately bent, as at 4, and extended at right angles, as at 5, and then further extended at right angles to provide an end-portion 6, 60 which latter at its free end is suitably bent to provide a manipulating handle 7. At its opposite end, bar or strip C is arcuately bent, as at 8, extended obliquely inwardly, as at 9, again arcuately bent, as at 10, and 65 then extended outwardly to provide an opposite end-portion 11 disposed in alignment with the opposite end-portion 6 and similarly formed with a manipulating handle 12.

Forming part of the fowl engaging or holding member of the appliance, is a leg-clamp D, which comprises a block 12 recessed and channeled, as at 13, to fit for 70 slidable adjustment on the body-member C, block 12 having threaded therein at set-screw 14 for engagement with body C in retaining the block D and its associate parts in selected or adjusted location relatively to table A. And pivoted, as at 15, 15', on block D, is a pair of co-operating opposed jaws 16, 16', respectively, formed upon their 75 opposed inner faces with spaced complementary approximately semi-circular recesses 17 jointly or co-operatively providing openings to accommodate clamping engagement with 80 the legs e of the particular fowl F being operated upon. At one end, the one jaw 16 is slotted, as at 18, to receive a threaded bolt or the like 19 pivotally attached at one end, as at 20, to the other jaw 16' and 85 adjustably carrying a wing-nut or the like 19a for detachably locking the jaws 16, 16', adjustably together in clamping or holding engagement with the fowl's legs, as illustrated in Figure 1.

Also forming part of the fowl engaging or holding member of the appliance, is a wing-clamp E, which similarly comprises a block 21 recessed and channeled, as at 22, 90 to fit for slidable adjustment preferably on the arcuate part 10 of the body-member C, block 21 having likewise threaded therein a set-screw 23 for engagement with the body-member C in retaining the block E and its associate parts in selected or adjusted location 95 relatively to table A. And pivoted, as at 24, 24', on block E, is a pair of co-operating opposed jaws 25, 25', respectively, concavely recessed upon their opposed inner faces, as at 26, for jointly or co-operatively 100

105

110

providing an opening to accommodate the fowl's wings *w* at the second joint thereof, as shown. Similarly, at one end, the one jaw 25 is slotted, as at 27, to receive a threaded bolt or the like 28 pivotally attached at one end, as at 29, to the other jaw 25' and adjustably carrying a wing-nut or the like 28^a for detachably locking the jaws 25, 25', together in clamping or holding engagement 10 with the fowl's wings, as illustrated; and suitably fixed at one end upon the outer faces of the jaws 25, 25', is a pair of opposed arcuate preferably somewhat yielding clamp-members or straps 30, 30', for holding engagement with the body of the fowl, also as illustrated in Figure 1.

In use, the body-member C is rested at its aligning extremities 6, 11, in the grooves 2 of the brackets 1. The particular upper jaws 20 now being swung to open position, as indicated in dot-and-dash lines in Figure 4, the fowl F is disposed upon the table A and its legs *e* and wings *w* disposed in the recesses 17 and 26 of the other jaws. The respective 25 pairs of jaws are now locked together, when the fowl is securely held and presented upon the table A for effecting with convenience and accuracy the desired operation, usually performed with instruments G. As the operation includes incisions from or upon both sides of the fowl, and the incision on one side being completed, the body-member C is readily engaged at its handles 7, 12, and reversed end for end, when the fowl, in a similar 30 convenient manner, is held and presented for the completing incision.

The operation being performed and completed, the jaws 16, 16', and 25, 25', are disengaged, when the treated fowl may be 40 easily removed without injury.

My new appliance thus enables the caponizing operation to be performed with convenience and precision; it is simple, inexpensive, and durable in structure, easily 45 usable, and efficient in the performance of its intended functions.

I am aware that changes in the form, construction, arrangement, and combination of

the several parts of my new appliance may be made and substituted for those herein 50 shown and described without departing from the nature and principle of my invention.

Having thus described my invention, what I claim and desire to secure by Letters Patent is:

1. A caponizing appliance including, in combination, a body-member, and means including pairs of opposed jaws disposed on the body-member for holding-engagement with the legs and wings of the fowl being 60 treated.

2. A caponizing appliance including, in combination, a body-member of rigid bar structure, and means including pairs of opposed jaws disposed for adjustment on the body-member for holding-engagement with the legs and wings of the fowl being treated.

3. A caponizing appliance including, in combination, a fowl engaging member including a block, a pair of opposed jaws mounted on the block, one of said jaws being swingable relatively to the other, and means on the jaws for detachably locking the same together.

4. A caponizing appliance including, in combination, a fowl engaging member including a block, a pair of opposed jaws mounted on the block, one of said jaws being swingable relatively to the other, means on the jaws for detachably locking the same together, and a pair of opposed body-engaging straps carried by the jaws.

5. A caponizing appliance including, in combination, a table, fixed brackets upstanding from the table, and a fowl-holding member comprising a body portion adapted for resting removably on said brackets.

6. A caponizing appliance including, in combination, a table, fixed recessed brackets upstanding from the table, and a fowl-holding member comprising a body-portion having handle-extensions adapted for resting removably in the recesses of the brackets.

In testimony whereof I affix my signature.

HARRY M. YOUNG.
